(57) **CLAIM**

The ornamental design for a chair, as shown and described.

DESCRIPTION

FIG. 1 is a top front left perspective view of a chair showing my new design;

FIG. 2 is a front left perspective view of the design shown in FIG. 1;

FIG. 3 is a front view of the design shown in FIG. 1;

FIG. 4 is a rear right perspective view of the design shown in FIG. 1;

FIG. 5 is a rear view of the design shown in FIG. 1;

FIG. 6 is a top front perspective view of the design shown in FIG. 1; and,

FIG. 7 is a left side view of the design shown in FIG. 1, the

right side view being a mirror image thereof.

The bottom of the chair forms no part of the claimed design.

1 Claim, 7 Drawing Sheets
